CLAIM

The ornamental design for a confectionery bottle, as shown and described.

DESCRIPTION

FIG. 1 is a perspective view of a confectionery bottle, showing our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken line disclosure forms no part of the claimed design.
